Patented June 24, 1924.

UNITED STATES PATENT OFFICE.

HOWARD T. CHINN, OF INGLEWOOD, CALIFORNIA.

DOLL.

Application filed April 12, 1923. Serial No. 631,708.

To all whom it may concern:

Be it known that I, HOWARD T. CHINN, a citizen of the United States, residing at Inglewood, in the county of Los Angeles and State of California, have invented a new and useful Doll, of which the following is a specification.

This invention relates to toys and more particularly to dolls having movable parts.

10. The object of the invention is to provide a device of this character constructed so that the depression of a button will operate to move certain parts of the toy which are spring returned.

15. Another object is to provide a cheaply constructed toy of this character which will afford amusement for children and which is comparatively strong and not easily broken.

20. With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

25. In the accompanying drawings:—

Figure 1 represents a front elevation of a doll constructed in accordance with this invention with the movable parts shown in raised position in dotted lines and in normal lowered position in full lines.

30. Fig. 2 is a longitudinal section taken on the line 2—2 of Fig. 1.

Fig. 3 is a similar view taken in a plane at right angles to Fig. 2, and

35. Fig. 4 is a horizontal section taken on the line 4—4 of Fig. 2.

The invention is herein shown in the form of a doll 1, although obviously it may be embodied in any other animal or object.

40. The body 2 of the doll which is preferably constructed of wood, papier-mâché or other suitable material is here shown with the head 3 made integral therewith and through which and said body extends centrally, a longitudinal bore 4 merging at its lower end into a chamber 5 and at its upper end into a chamber 6 for a purpose presently to be described. A bore 7 extends transversely through the body at the upper portion thereof adjacent the shoulders of the doll and

45. 50. 55. in the outer ends of which are movably

mounted arms 13 connected for operation in a manner presently to be described.

A transverse bore 8 leads from the chamber 5 and opens through the rear portion of the body having an upwardly extending enlargement 9 as shown clearly in Fig. 2 in which enlargement the actuating push button 20 is designed to operate.

The lower end of the body 2 has spaced leg receiving sockets 10 in which legs 11 are mounted to rotate and be held in adjusted position by friction. These legs 11 are equipped at their lower ends with flat feet 12 designed to support the doll in upright position.

As shown, the head 3 of the doll is equipped with bobbed hair 14 connected centrally to a plate or button 15 mounted on the upper end of a rod 16 which extends through the bore 4. This rod 16 is loosely connected at its lower end in the chamber 5 with the inner end of the lever 17 fulcrumed at 18 in the chamber 9, the outer end of said lever being deflected upwardly and equipped with the push button 20. The inner end of this lever has a hook 19 as shown in Fig. 2 which operates to retain the ring 26 which connects it with the rod 16.

Two passages 21 and 22 extend upwardly from the chamber 5 and diverge, merging at their upper ends into the transverse bore 7 near its outer ends and in which are mounted for longitudinal movement, rods 23 and 24 loosely connected at their upper ends with eyes 13^a carried by the inner ends of the arms 13 while their lower ends have eyes 25 loosely connected with the inner end of the lever 17.

A coiled spring 27 is mounted on the upper end of the rod 16 in the chamber 6 and is connected at one end with a button 15 and bears at its other end against the lower end wall of chamber 6 so that when the rod 16 is moved longitudinally downward, this spring will be compressed and simultaneously the hair 14 will be lifted as shown in dotted lines in Fig. 1. The movement of the rod 16 in the opposite direction will relieve the tension of spring 27 which will expand and seat the hair causing it to closely hug the head as shown clearly in Figs. 2 and 3.

The means employed to retract the rod 16 against the tension of spring 27 compresses the lever 17 and its operating push button 20. It will thus be seen that when the button 20 is depressed to move it upwardly into

chamber 9, the inner end of said lever will swing downwardly and carry with it the rods 16, 21 and 22, thereby raising the hair 14 and the arms 13 into the dotted line position shown in Fig. 1. Immediately this button is released the spring 27 will return the parts to normal position.

While the invention is shown embodied in a doll obviously it may be used in a toy 10 of any other configuration having movable parts operated by the depression of the push button 20.

Various changes in the form, shape, proportion and other minor details of construction 15 may be made without departing from the principle or sacrificing any of the advantages of the claimed invention.

I claim:

1. A toy of the class described comprising 20 a body having a head with a bore extending longitudinally through both, other bores communicating with the lower end of said first mentioned bore and diverging upwardly, rods mounted to reciprocate in said bores, 25 movable elements connected with the upper ends of said rods, a lever connected with the opposed ends of said rods and designed to be rocked to simultaneously move the rods in one direction, and a coiled spring 30 for moving them in the opposite direction.

2. A toy of the class described comprising 35 a body having a head at one end thereof, a bore extending longitudinally through said body and head and enlarged at its opposite ends to form chambers, a rod mounted to reciprocate in said bore and chambers, a movable element connected with one end of said rod, a coiled spring mounted

on said rod end and connected with said movable element, bores extending from the 40 chamber at the opposite ends of said first mentioned bore and diverging, rods mounted in said diverging bores and projecting into said chamber, movable elements connected on opposite ends of said rods, a lever fulcrumed 45 in said body and having its inner end extending into said chamber and loosely connected with said rods, and means for rocking said lever whereby the movable elements are moved in one direction, said spring operating to move them in the opposite direction.

3. A toy of the class described comprising a body having a head with a bore extending longitudinally through said head and body, 55 a bore extending transversely through said body adjacent its connection with the head, arms movably mounted in the outer ends of said transverse bore, bores connecting the outer ends of said transverse bore, rods 60 mounted in said connecting bores and connected to actuate said arms, a rod mounted in said longitudinal bore and connected at its lower end with said arm actuating rods, means for moving said rods in one direction, 65 a spring for moving them in the opposite direction, and a movable element connected with the outer end of said longitudinal rod.

In testimony that I claim the foregoing as my own, I have hereto affixed my signature in the presence of two witnesses.

HOWARD T. CHINN.
